ANCHORING DEVICE

Enno Becker, Bremen, Germany

Application June 17, 1933, Serial No. 676,375
In Germany June 16, 1932

5 Claims. (Cl. 61—60)

The invention relates to an improvement in anchoring devices for steel sheet pilings of the type which are shiftable into the piling from above.

- 5 In order to reduce the bearing width and in accordance therewith the bending moment and the required profilation of the sheet piling anchoring devices are arranged below the water level with sheet piling irons which are to be 10 used in considerable depth of water. For this purpose constructions have been proposed which can be shifted into the sheet piling from above the water level, so that the expensive diving work is avoided.
- 15 The constructions of that type hitherto known are, however, accompanied by serious drawbacks. Either they comprise large anchoring bodies which are moved within channels formed by the shape of the sheet piling irons or they comprise 20 anchoring heads moved within smaller grooves. The first mentioned construction has the disadvantage that the anchoring body is massive and its manufacture is expensive. Moreover such channel like piling irons cannot be manufactured by rolling and in view of the possible deformation of the piling irons during ramming a 25 firm and tight engagement of the anchoring body is not secured. The second mentioned proposal to provide smaller grooves has been embodied by 30 constructions in which the projecting parts forming the grooves consisted of two separate strips secured to the piling, so that not only a double securing is necessary, but also the danger exists, 35 that the projecting parts forming the grooves are liable to be spread apart by slightly excessive strains. Consequently only limited strains can be transferred by these constructions.

The invention comprises a construction in which all these disadvantages are avoided by 40 manufacturing the projecting part in which the groove is formed from a single working piece and carrying through to a certain extent the anchoring head which must be pushed into the piling in the longitudinal direction of the groove. In 45 this way it becomes possible to transmit such high strains as are to be taken up by anchors of sheet piling irons.

The invention will be more clearly illustrated 50 by reference to the accompanying drawing in which

Fig. 1 shows an upper view,

Fig. 2 is a cross section of a piling wall provided with the anchoring device according to 55 the invention,

Fig. 3 represents the line of distribution of the bending moments according to Fig. 2.

Fig. 4 shows a cross-sectional detail of an embodiment of the anchoring device on an enlarged scale.

Fig. 5 is a cross-section of a modified form of the sheet piles to be anchored.

Fig. 6 shows a further form of the anchoring device.

Fig. 7 shows the cross-section of a sheet pile 10 similar to Fig. 5.

Upon each of the sheet piling irons *a* is welded a member *b* with a groove-like slot extending lengthwise of the member, the member extending above the water line *d—d*. A connecting 15 member *c* with a beaded head *x* is shifted into the groove provided by the member *b*. The anchoring device *h* is connected to the connecting member *c* in any suitable way, for instance by articulated joints.

Said construction has the following advantages: It is not necessary to weaken the piles by boring therethrough holes serving for connecting the anchor. The grooved member can be easily manufactured from a single uniform work 20 piece by rolling or planing. The grooved member must only be extended over the required length of the pile and the pile is strengthened over the length of the largest bending strain 25 *f—f* by the grooved member and the connecting member. Compared with known constructions considerable advance is obtained in respect of 30 the manner of manufacture, of economy and of the most suitable kind of construction which secures safeness from the static point of view. 35

As shown in Fig. 4, the beaded head *x* of the connecting member *c* is rounded off in such a manner that within the groove of the member *b* there is possible a turning movement about the longitudinal axis of the head. Thereby it becomes possible 40 angularly to dispose the anchors in respect of the axis of the wall without the necessity of inserting a special articulation.

In Fig. 5 the groove *g* is provided in the sheet piling wall member itself. In this case the application and connection of a special connecting member is unnecessary.

In Fig. 6 two connecting members *c* are joined to one anchor *h*. The grooved member *b* is welded to each group of two Z-shaped irons.

In Fig. 7 the member *c* has an I-like shape. It may be used for strengthening the piles also in such cases in which no anchors are to be joined.

The kind of sheet piling walls to which the 55

grooved member is connected, or into which the grooves are rolled, is immaterial. Moreover it is of no importance whether the joinings are positioned at the exterior or at the interior of the wall and whether one or several piles are joined 5 simultaneously.

What I claim to secure by Letters Patent in the United States is:

1. Anchoring device shiftable from above for sheet piling walls comprising projections at the 10 piling forming between them a groove, the said projections being made of one piece, and an anchoring member adapted to engage and slide into the groove, the said anchoring member extending over a certain length of the groove.

15 2. Anchoring device shiftable from above for sheet piling walls comprising projections at the piling forming between them a groove, the said projections being integral with the piling, an anchoring member adapted to engage and slide 20 into the said groove, the said anchoring member extending over a certain length of the groove, and means pivotally connected with the anchoring member to actuate said member.

25 3. Anchoring device shiftable from above for sheet piling walls comprising a grooved member secured to the piling, a connecting member hav-

ing a beaded head portion adapted to engage and slide into the groove of the said grooved member, the said connecting member being extended over a certain length of the grooved member, and an anchor joined to the connecting member.

4. Anchoring device shiftable from above for sheet piling walls comprising projections on the piling forming a groove between them, the said projections being integral with the piling, a connecting member provided with a beaded head portion adapted to engage and slide in the said groove, the said beaded head portion being extended over a certain length of the groove and rounded off at its lateral faces so that the connecting member may be turned in the groove 15 about a longitudinal axis, and an anchor pivotally connected with the said connecting member.

5. Anchoring device shiftable from above for sheet piling walls comprising two grooved members welded to the piling, two connecting members each having a beaded head portion adapted to engage and slide in the groove of one of the grooved members, the said beaded head portions being extended over a certain length of the grooved members, and a single anchor pivotally 25 connected with the two connecting members.

ENNO BECKER.
